UNITED STATES PATENT OFFICE.

HIRAM J. HALLE, OF NEW YORK, N. Y., ASSIGNOR TO ELLIOTT-FISHER COMPANY, OF NEW YORK, N. Y., A CORPORATION OF DELAWARE.

TYPE-WRITING MACHINE.

No. 856,344

Specification of Letters Patent.

Patented June 11, 1907,

Application filed September 11, 1905. Serial No. 277,980.

To all whom it may concern:

Be it known that I, HIRAM J. HALLE, a citizen of the United States, residing at New York, in the county of New York and State 5 of New York, have invented a new and useful Type-Writing Machine, of which the following is a specification.

This invention relates to typewriting machines, more especially machines known as 10 flat platen or book typewriters, and is directed more particularly to the production of an efficient line space tabulator, that is to say, a mechanism whereby relative movement of the platen and printing mechanism in the direction of line spacing will be arrested at one 15 or more predetermined points to properly locate the entries or records to be typewritten upon the work sheet.

The object of the invention is to provide a 20 line space tabulator, consisting of a catch and a series of stops, the catch and stops being carried respectively by those elements of the machine which are movable to effect the line spacing of the work, and being related so 25 that the catch will engage a stop to arrest the line spacing movement at the proper point without attention on the part of the operator other than that required to move the catch into position to be subsequently engaged by 30 the stop.

To the accomplishment of this object, the 35 illustrated embodiment of the invention includes a depressible catch, mounted on and movable with the frame of a flat platen typewriter, and coöperating with stops associated with the platen and arranged in a series disposed longitudinally thereof, the depression of the catch presenting the same in a path 40 obstructed by a stop to arrest the frame when the printing mechanism carried by the latter has arrived at the proper point opposite the work sheet.

The invention also resides in certain other 45 features construction and arrangement, to be hereinafter described, illustrated in the accompanying drawings, and defined in the appended claims.

In said drawings—Figure 1 is a perspective view of an Elliott-Fisher typewriter 50 equipped in accordance with this invention. Fig. 2 is a front elevation of a portion of the machine, showing the tabulating mechanism on a somewhat enlarged scale, and Fig. 3 is a vertical section on the line 3—3 of Fig. 2.

Each part is indicated by the same number in all of the views.

The Elliott-Fisher typewriter includes in its organization a stationary flat platen 1 equipped with longitudinal tracks or guides 2 and 3. Above the platen 1 is disposed the machine proper, which includes a frame 4, movable longitudinally of the platen upon the tracks or guides to space the lines of writing on the work sheet, and supporting a traveling carriage 5 which carries the printing mechanism and is movable transversely of the platen on the frame 4 to letter space the writing. The tracks 2 and 3 are toothed, as shown.

Mounted on the machine frame 4 and in advance thereof is the line spacing mechanism, comprising a transverse spindle 6, pinions 7 fixed thereon and meshing with the toothed tracks, an oscillatory line spacing actuator 8 for rotating the spindle and pinions, 75 and stop mechanism 9 for determining the throw of the actuator 8 to regulate the width of the spaces between the lines of writing.

The structure thus far described is common to the Elliott-Fisher machine and constitutes no part of my present invention, except in so far as it may enter into new and useful combination with the tabulating mechanism to be described.

At the front side of the frame, adjacent to the left hand end thereof, is located a depressible catch 10 in the form of a vertically disposed bar mounted to reciprocate in guides 11, 12 and 13, the guide 11 being attached to the top of the frame 4 and the guides 12 and 13 being formed at the opposite ends of a guide bracket 14 secured to the lower part of the frame. The catch 10 is provided with a pin 15 extended through a vertically disposed slot 16 in the bracket 14 to prevent the catch from turning. The catch is normally held in its elevated position by a spring 17 encircling the catch and interposed between the guide 12 and a collar 18 fixed on the catch and having a projecting finger piece, 100 key, or handle 19, by means of which the catch is depressed against the resistance of the spring 17. The lower end of the catch 10 is flattened, as indicated at 20, but its extremity is too large to be received within the normal spaces between the teeth of the track 2 directly over which the catch is mounted. At predetermined, though not necessarily

regular intervals, the track 2 is formed with notches 21 of sufficient width to receive the lower end of the catch 10, these notches being formed in any suitable manner, as by removing or omitting certain of the rack teeth. The end walls of these notches constitute stops 22 and 23, accordingly as the catch is utilized to arrest the machine in its movement forward or back. Ordinarily, however, the tabulating mechanism is not utilized in connection with the rearward movement of the machine, but is brought into action to arrest the printing mechanism at successive points in its forward advance.

15 The notches 21 are located in the track 2 in a manner appropriate to the particular work to be done. For instance, the first of these notches, to-wit, the one nearest the rear end of the platen, may be so located that 20 when the catch enters therein and the machine is arrested, the latter will be in position to print a heading; the next notch being positioned to cause the arrest of the machine in position to print the body of a record, and the last notch being utilized to locate the machine in position to enter footings, totals, or the like.

25

Of course it will be understood that this line space tabulating mechanism is simply 30 utilized to arrest the free movement of the machine over the platen, so as to position it for the making of a record at the proper point, the usual line spacing mechanism being utilized to line space the record in the ordinary manner.

Assuming that the machine is at the rear end of the platen, where it is usually positioned during the adjustment, removal, or replacement of a work sheet, the operator, by 40 placing her finger upon the key 19, depresses the catch 10 upon the top of the rail 2. Pressure upon the key 19 is maintained, and the machine is drawn forward until the catch arrives opposite and enters the first notch, thus 45 arresting the machine in position for the first entry upon the work sheet. The key 19 is then released and the catch is restored or elevated by the spring 17. The operator now proceeds to make the entry, utilizing the line 50 spacing mechanism if said entry embraces more than a single line of writing. The catch is then depressed and the machine drawn forward, as before, until arrested by the next stop in position for the next entry.

55 It is of course obvious that instead of utilizing one of the ordinary tracks or guides as a stop carrying bar, a separate stop bar might be mounted at one side of a track, and either notched or provided with either stationary or 60 adjustable stop projections. In fact, so far as the broad novelty of the invention is concerned, it is immaterial which of the relatively movable elements of the machine carries the stop or catch, respectively, or whether 65 the movable machine element is the printing

mechanism or platen, or whether the latter is of the round or flat type, since it is believed to be new to provide line space tabulating mechanism designed to supplement the ordinary line spacing mechanism by arresting the free movement of the movable machine element at the proper point or points to begin the printing of a record or separated records, or separated parts of the same record.

In other words, while it is thought that the 75 illustrated embodiment of the invention will be fully comprehended from the foregoing description thereof, I desire to be understood as reserving the right to effect such changes, modifications, and variations of 80 the illustrated structure as may come fairly within the scope of the protection prayed.

What I claim is:—

1. In a typewriter, the combination with a platen and printing mechanism relatively 85 movable in the direction of line spacing, of line spacing mechanism, and line space tabulating mechanism for arresting the relative movement of the platen and printing mechanism in the direction of line spacing to facilitate the printing of separated records or entries.

2. The combination with a typewriter including a flat platen and a machine frame which are relatively movable for line spacing, and printing mechanism mounted on the frame and movable for letter spacing, of line spacing mechanism, and line space tabulating mechanism arranged to arrest the relative movement of the machine frame 95 and platen in the direction of line spacing at predetermined points, to facilitate the printing of separated records or entries.

3. The combination with a typewriter including a flat platen, a machine frame mounted to travel thereover in the direction of line spacing, and printing mechanism movable on said frame in the direction of letter spacing, of line space tabulating mechanism including stops and a coöperating catch, carried respectively by the platen and machine frame and arranged to be brought into engagement by the travel of said frame in the direction of line spacing.

4. The combination with a typewriting 115 machine including a flat platen, a machine frame movable thereover for line spacing, and a carriage movable on the frame for letter spacing, of a series of stops associated with the platen, and a catch mounted on the machine frame and movable into and out of a path obstructed by the stops in the free movement of the frame in the direction of line spacing.

5. The combination with a typewriting 125 machine including a flat platen, a machine frame mounted to travel thereon, a carriage movable on the frame, a stop bar associated with the platen and equipped with a series of stops, and a catch movable with the ma- 130

chine frame and also movable into and out of position to be engaged by a stop and thus arrest the movement of the frame in the direction of line spacing.

5 6. The combination with a typewriting machine including a flat platen and a machine mounted to travel thereover for line spacing, of a notched bar associated with the platen, and a catch movable with the machine and arranged to enter one of the notches to arrest the machine in position for the printing of a record or entry.

15 7. The combination with a typewriting machine including a flat platen and a machine frame mounted to travel in the direction of line spacing, of line spacing mechanism for said machine, a series of stops disposed along one longitudinal edge of the platen, and a depressible catch carried by the machine and coöperating with the stops to arrest the movement of the frame in the direction of line spacing.

25 8. The combination with a typewriting machine including a flat platen, tracks or guides, and a machine mounted to travel on said tracks or guides in the direction of line spacing, of a series of stops carried by one of said tracks or guides, and a catch carried by the machine and disposed to cooperate with said stops to arrest the machine at different points when said machine is advanced freely in the direction of line spacing.

35 9. The combination with a typewriting machine including a flat platen, tracks or guides one of which is provided with a series of notches, and a machine mounted to travel on said tracks or guides in the direction of line spacing, of a catch mounted on the machine and depressible into engagement with the notches in the track or guide.

45 10. The combination with a typewriting machine including a flat platen, tracks or guides, and a machine mounted to travel on said tracks or guides in the direction of line spacing, of line spacing mechanism for the machine, and line space tabulating mechanism including means carried by the machine frame and coöperating with one of the tracks or guides to arrest the machine at predetermined points as said machine is advanced freely independently of the line spacing mechanism in the direction of line spacing.

55 11. The combination with a flat platen and tracks one of which is provided with stops located at intervals, of a machine frame mounted to travel on the tracks, printing mechanism mounted to travel on the frame, and a vertically disposed catch mounted on the machine frame adjacent to one end thereof and longitudinally movable into position to engage the stops with which one of the tracks is provided, a finger piece for the manipulation of the catch, and a spring normally retaining the catch in an 65 inoperative position.

12. The combination with a flat platen and toothed tracks, of a machine frame mounted to travel on the toothed tracks to line space the writing, a carriage mounted to travel on the frame to letter space the writing, line spacing mechanism carried by the traveling frame and engaging the teeth of the tracks to advance the frame step-by-step for line spacing, and line space tabulating mechanism separate from and independent of the line spacing mechanism and including a series of stops carried by one of the toothed tracks and a vertically movable catch mounted on the frame and depressible into interfering relation with a stop to arrest the frame when the latter is advanced freely and independently of the line spacing mechanism.

70 13. In a typewriting machine, the combination with a flat platen, a machine frame mounted to travel thereover for line spacing, and printing mechanism movable on the frame for letter spacing, of line spacing mechanism operative to advance the frame step-by-step to line space the writing, and line space tabulating mechanism arranged 85 to arrest the free forward advance of the machine when the latter is freely moved or skipped from one writing area to the next independently of the line spacing mechanism, said line space tabulating mechanism 90 including a series of stops, disposed longitudinally of the platen adjacent to one side edge thereof, and a manually operated catch mounted on the machine frame, at the front side thereof, and movable from its normal 95 inoperative position to a position in which the free forward movement of the machine will present said catch to one of the stops and thus arrest the machine frame opposite a new printing area of a work sheet supported 100 by the platen.

105 14. In combination, a typewriting machine including a flat platen and a machine frame, relatively movable longitudinally of the platen for line spacing, a carriage movable on the frame for letter spacing, printing mechanism on the carriage, line spacing mechanism including a manually operated actuator, a normally inoperative line-space-tabulator catch movable to its operative position, the line space actuator and the tabulator catch being disposed adjacent to opposite ends of the frame to permit one to be operated by the right hand and the other by the left hand of the operator, and a series of 110 stops disposed longitudinally of the platen and arranged to coöperate with the catch to arrest the relative movement of the platen and frame in the direction of line spacing.

115 15. The combination with a flat platen and toothed tracks, of a machine frame mounted to travel on the toothed tracks to line space the writing, a carriage mounted to travel on the frame to letter space the writing, line spacing mechanism carried by the 120 130

traveling frame and engaging the teeth of the tracks to advance the frame step by step for line spacing, a line-space-tabulating mechanism separate from and independent of the line-spacing mechanism and including a series of stops mounted independently of the machine frame, and a vertically movable catch mounted on a frame and depressible into interfering relation with a stop to arrest the frame when the latter is advanced freely

and independently of the line-spacing mechanism in the direction of line spacing.

In testimony, that I claim the foregoing as my own, I have hereto affixed my signature in the presence of two witnesses.

HIRAM J. HALLE.
